ADJUSTABLE BURIAL CASKET

Patrick D. Skahen, Syracuse, N. Y.

Application December 4, 1936, Serial No. 114,215

15 Claims. (Cl. 27—4)

This invention relates to burial caskets and has for its primary object a burial casket of standard size which is adjustable for bodies of different widths, so that a casket of standard or minimum size can be used for the smallest or largest bodies. In this connection, attention is called to the fact that heretofore, caskets for the bodies of adults have been in several sizes or widths, from 22½ or 23 inches to 28 inches, that is, with the body supporting surface from substantially 22½ or 23 to 28 inches, and the casket of the required width selected for the particular body. This condition requires that the undertaker keep in stock caskets of the various widths in each class or style and also increases the cost and retail prices compared with this burial casket adjustable for different sizes or widths of bodies.

It also has for its object a casket including a base and a boxlike lid hinged along one of its longitudinal edges to the base with an adjustable wing or wings movable or shiftable to an extended position to give a roomy wide effect to the base, when the lid is open and into a position to be within the outline of the base to permit closing of the lid.

It further has for its object a simple and economical base construction for coacting with the boxlike lid.

Other objects will appear throughout the specification.

The invention consists in the novel features and in the combinations and constructions hereinafter set forth and claimed.

In describing this invention, reference is had to the accompanying drawings in which like characters designate corresponding parts in all the views.

Figure 1 is a side elevation of this casket with the lid being open.

Figure 2 is an enlarged sectional view on the line 2—2, Figure 1.

Figure 3 is a fragmentary detail view showing the hinge between the wings and the parts to which they are hinged.

Figure 4 is a fragmentary detail view of the end wing and one of the side wings showing the interlock between the same when they are in closed position.

This casket comprises, generally, a comparatively flat tablelike base, a boxlike lid hinged along one of its longitudinal edges to the base, an adjustable or shiftable wing or wings arranged to provide lateral extensions of the body supporting surface of the base and shiftable later-

ally to give a wide roomy appearance, when the lid is open, and movable inwardly, so as not to interfere with the closing of the lid, all whereby a casket of minimum size can be adjusted for larger bodies so that a casket of standard size can be supplied, which will receive, without giving a crowded appearance, bodies of all sizes or widths.

1 designates the base; 2 the lid. The base is here shown as formed of lower and upper sheet metal sections 3, 4, these being shown as rectangular and formed with bottom, side and end walls with the lower section arranged inverted, so that the bottoms of the two sections overlie each other. The lower section is of greater length and width than the upper section and the upper section arranged concentric with the lower section, thereby providing a ledge at 5. The bottoms of the two sections are secured together in any suitable manner, as by welding. Preferably, a marginal frame 6 of wood is arranged in the lower section, and the margins of the side and end walls are turned inwardly at 7 to provide a channel in which the marginal frame 6 is seated. A suitable mattress, indicated at 8, is located in the upper section 4 with its upper body supporting surface above the upper edges of the side walls of the upper section 4. The lid 2 is also formed up of sheet metal to have a dome-shaped top 9, side and end walls 10 and 11 and rectangular beads 12, 13 are located at the upper and lower margins of the side and end walls 10, 11. The beads 12, 13 not only strengthen the sheet metal structure but also cause the side and end walls to be inset or have a panel appearance. A margin frame 13a of wood is located in the bead 13.

The lid is hinged at 14 along one longitudinal lower edge to the base 1 or the ledge 5 and when closed, the lid seats throughout the entire length of its lower edge on the ledge 5.

As here shown, hinge leaves 15 are mounted on the ledge 5 through which the hinge pins 14 extend into the lid. The lid is held closed in any suitable manner.

In the illustrated embodiment of my invention, the means by which the casket is adjustable for receiving bodies of different widths or by which wider bodies do not have a crowded appearance when in a casket of minimum width, comprises one or more wings adjustable widthwise relatively to the base and movable into a position, whereby they do not interfere with the closing of the lid, when the lid is closed.

As here illustrated, two adjustable wings are 55

provided extending along the front and rear longitudinal edges of the base. 16 and 17 designate respectively these wings, the wing 17 being located within the lid and hinged at 18 to one of the side walls of the lid near but spaced apart, in a radial direction, from the hinge 14 of the lid. The wing 16 is hinged at 19 to the upper margin of the outer side wall of the upper section 4 of the base 1. Both wings extend above the plane of the body supporting surface of the base 1 or above the surface of the mattress 8 and are movable into different inclinations to accommodate bodies of different widths. They are also movable upwardly into an upright position to permit the closing of the lid. The hinges 18 and 19 are built to work with sufficient friction to remain in any angular position. The wing 17 has a shield 20 hinged at 21 thereto and extending across the space between it and the upper section 4 of the base, this shield being usually of sheet metal. Means is provided for limiting the pivotal movement of the wing 17 about its hinge in either direction. This means is here shown as a slot 22 formed in the shield 20 and a pin or stop 23 extending through the slot and into one of the side walls of the upper section 4, so that the extent of pivotal movement of the wing 17 depends upon the length of the slot 22. This is for the purpose of preventing undue crowding of a particularly wide body when the lid is closed. Also, a similar wing 24 is provided at the head end of the base 1, this being hinged to the end wall of the base in the same manner as the wing 16 is hinged to the side wall 35 of the upper section of the base. This end wing 24 and the wing 16 are provided with means for locking them together when both are folded into upright position, preliminary to closing the lid. As here shown, one of the wings, as the end wing 24, is provided with a flat pivoted hook 25, the bill of which enters a suitable eye or recess 26 in the end of the wing 16.

The adjustable wings in the illustrated embodiment of my invention extend about half of the length of the base, and there is an additional wing 27 forming a continuation of the wing 16, this extending along the side of the foot end of the base.

28 designates an inner cover or lid for covering the lower half of the body. This is here shown as hinged to the lid on an axis coextensive with the axis 18 of the wing 17 with the side wall 29 thereof forming a continuation of the wing 16 when the lid 2 is closed. The free edge of this lid 55 coacts with the upper edge of the wing 27.

After the body is laid out by the undertaker in the casket, the lid 28 is closed in the position shown in Figures 1 and 2, it closing against the edge of the wing 27.

60 A casket with a half inner lid 28 is called a half-couch, as the lower half of the body only is covered by an inner lid 28. In a full-couch casket, the lid 28 is omitted.

The inner surfaces of the lids and the wings 65 are covered with a suitable ornamental lining.

In operation, for a relatively small or slim adult body, the wings 16, 17 may be adjusted to a nearly vertical position, and for wider bodies, the wings are moved outwardly on their hinges 70 into greater inclinations. When the casket is to be closed, the wings 16 and 24 are moved into an upright position and interlocked together by the hook 25. The wing 16 comes into alignment with the wing 27, which is provided with a suitable latch 33 at the margin thereof movable from

the position shown in Figure 1 into a horizontal position to hold the wing 16 from outward displacement or hold the wing 16 flush with the wing 27. The wing 27 is held from outward displacement by reason of the fact that it laps at 35 under the margin at the outer side of the inner lid 28. Thus, the wings 24 and 16 are moved into position where they do not interfere with the closing of the lid 2. When the lid 2 is closed, the wing 17 being pivoted at a point radially to the outward relatively to the hinge 14 of the lid, moves slightly inwardly, until limited by the pin or shoulder 24 coming into engagement with one end of the slot 22, so that the wing 17 does not interfere with the closing of the lid by coming into engagement with the side wall thereof to which it is pivoted. During closing movement of the lid 2, the inner lid 28 will also incidentally move slightly upwardly therewith but this is of no consequence, as it does not move the inner lid 28 far enough to interfere with the closing of the lid. It is obvious that by reason of the adjustable wings 16 and 17 or either of them, one casket of standard size may be used for adult bodies of different widths, and in all cases, a 25 roomy uncrowded effect is given.

This casket, owing to its adjustability, effects a great saving in cost of manufacture and in funeral cost, and it further effects a great saving, as the undertaker instead of carrying a large 30 stock of various sizes can carry but a few in any one style.

What I claim is:—

1. A burial casket comprising a base element having a body supporting surface, a boxlike lid element closable on the margin of the base element having side and end walls which form the sides and ends of the casket when closed, and which coact with the base element near the level of said body supporting surface, and means normally extending laterally beyond the base element and forming an extension of the body supporting surface thereof, said means being shiftable into a position within the outline of the base element to permit closing of the lid element. 45

2. A burial casket comprising a base element having a body supporting surface, a boxlike lid element closable on the margin of the base element, and means normally extending laterally beyond the base element and forming an extension of the body supporting surface thereof, said means being shiftable into a position within the outline of the base element to permit closing of the lid element, the lid element being hinged to one margin of the base element and said means including a wing carried by the lid element and movable therewith during closing of the lid element into position to permit the lid element to close down on the base element. 55

3. A burial casket comprising a base element having a body supporting surface, a boxlike lid element closable on the margin of the base element, and means normally extending laterally beyond the base element and forming an extension of the body supporting surface thereof, said means being shiftable into a position within the outline of the base element to permit closing of the lid element, the lid element being hinged to one margin of the base element, and said means including a wing hinged to the margin of one side wall of the lid element at a point parallel to and radially spaced from the hinge of the lid element, whereby the wing is movable upward and inward during closing of the lid element into 70 75 75

position to permit the lid element to close down on the base element.

4. A burial casket comprising a base element having a body supporting surface, a boxlike lid element closable on the margin of the base element having side and end walls which form the sides and ends of the casket when closed, and which coact with the base element near the level of said supporting surface, and means normally extending laterally beyond the base element and forming an extension of the body supporting surface thereof, said means being shiftable into a position within the outline of the base element to permit closing of the lid element, said means including adjustable wings extending along opposite side margins of the base element.

5. A burial casket comprising a base element having a body supporting surface, a boxlike lid element closable on the margin of the base element, and means normally extending laterally beyond the base element and forming an extension of the body supporting surface thereof, said means being shiftable into a position within the outline of the base element to permit closing of the lid element, said means including wings extending laterally and upwardly above the surface of the base element, one wing being hinged to the base element and the other to the hinged margin of the lid element, the wings being shiftable on their hinges from an outward inclination toward the vertical to permit closing of the lid element on the base element.

6. A burial casket comprising a tablelike base element having a body supporting surface, a boxlike lid element hinged to the base element and closable on the margin of the base element having side and end walls which form the sides and ends of the casket when closed, and which coact with the base element near the level of said body supporting surface, and a wing movably mounted on and shiftable relatively to one of said elements, and arranged to form a side wall for the base, the wing being movable into position to come within the margin of the lid to permit closing of the lid element.

7. A burial casket comprising a tablelike base element having a body supporting surface, a boxlike lid element hinged to the base element and closable on the margin of the base element, and a wing hinged to one of said elements near the plane of the body supporting surface of the base element and forming an upwardly and laterally extending wall for the base element, the wing being movable about the axis of its hinge to within the outline of the base element into position to permit closing of the lid.

8. A burial casket comprising a tablelike base element having a body supporting surface, a boxlike lid hinged to the base and closable on the margin of the base element having side and end walls which form the sides and ends of the casket when closed, and which coact with the base element near the level of said body supporting surface, a wing movably mounted on the base and extending laterally beyond the edge of the base providing an extension of the body supporting surface of the base, said wing being movable into a position to come within the margin of the base to permit closing of the lid.

9. A burial casket comprising a tablelike base having a body supporting surface, a boxlike lid hinged to the base and closable on the margin of the base, and a wing carried by the lid and movable relatively thereto, the wing being arranged within the lid and to extend from below

to above the body supporting surface of the base, when the lid is open.

10. A burial casket comprising a tablelike base having a body supporting surface, a boxlike lid hinged to the base and closable on the margin of the base, and a wing hinged to the lid near the lower edge thereof at a point spaced radially from the hinge connecting the lid to the base, the wing extending from below to above the body supporting surface of the base.

11. A burial casket comprising a tablelike base having a body supporting surface, a boxlike lid hinged near its lower edge to the base and closable on the margin of the base, wings extending along opposite margins of the base and forming lateral extensions of the body supporting surface of the base, and adjustable into different angular positions and being also movable into a position to come within the lid, when the lid is closed, and the other wing being hinged to the lid near the hinged lower edge thereof and to the outward radially relatively to the hinge between the lid and the base.

12. A burial casket comprising a tablelike base element having a body supporting surface, a boxlike lid element hinged at its lower edge to the base and closable on the margin of the base, laterally adjustable wings, each carried by one of said elements at the side edges of the base and forming extensions of the body supporting surface of the base and shiftable into positions to come within the outline of the base to permit closing of the lid, the lid element including side and end walls which form the side and end walls of the casket when closed, the lid coacting with the base near the level of the body supporting surface.

13. A burial casket comprising a tablelike base element having a body supporting surface, and a boxlike lid element hinged to the base element and closable on the margin thereof, a wing movably mounted on one of said elements and extending laterally beyond the outline of the base element forming a lateral continuation of the body supporting surface of the base element, another wing hinged to the base element at one end thereof and extending beyond the end of the base element and forming a lineal continuation of the body supporting surface of the base element, the wings being movable into an upright position to come within the outline of the base element, when the lid element is closed, the boxlike lid having side and end walls which constitute the side and end walls of the casket when closed, said end walls coacting with the base near the level of the body supporting surface.

14. A burial casket comprising a tablelike base having a body supporting surface, a boxlike lid hinged along one of its lower edges to the base beneath the plane of the body supporting surface and closable on the margin of the base, wings extending lengthwise of the longitudinal edges of the base and arranged to form lateral extensions of the body supporting surface of the base, one of the wings being hinged to the base and the other being hinged to the lid within the same at a point radially outwardly relatively to the axis of the lid, the wings being adjustable into different angular positions and movable into a position within the margin of the base, to permit closing of the lid.

15. A burial casket comprising a base including lower and upper sheet metal parts, each having a bottom, side and end walls, the lower part being inverted so that its bottom is upward and

- the margins of the lower part extend beyond the sides and ends of the upper part forming a ledge, the bottoms being secured together, the base being provided with a body supporting surface, and a boxlike lid having top, side and end walls, one of the side walls being hinged to the base on the ledge thereof, the lower edge of the lid resting on said ledge, when the lid is closed, a wing hinged to the lid within the same at a point to 5
10 the outward radially relatively to the hinged axis of the lid and extending upward beyond the

plane of the body supporting surface of the base and adjustable into different angular positions, a wing hinged to the lengthwise side of the base opposite to that on which the former wing is located and extending above the body supporting surface of the base and being also adjustable into different angular positions and movable into a position to come within the outline of the base to permit closing of the lid. 5

10

PATRICK D. SKAHEN.
